UNITED STATES PATENT OFFICE.

SIMON N. GAZAN, OF SAVANNAH, GEORGIA.

EYE-SHIELD FOR HEAD-COVERINGS.

1,209,284.

Specification of Letters Patent. Patented Dec. 19, 1916.

Application filed September 18, 1916. Serial No. 120,750.

To all whom it may concern:

Be it known that I, SIMON N. GAZAN, a citizen of the United States, residing at Savannah, in the county of Chatham and State 5 of Georgia, have invented certain new and useful Improvements in Eye-Shields for Head-Coverings, of which the following is a specification.

My invention relates to a new and useful 10 improvement in eye-shades or eye-shields, and has for its object to provide a device adapted for all headgear not provided with a fixed brim, vizor, or peak, particularly the fez, and affords a suitable and efficient shade 15 or shield from the sunlight, which device is of exceedingly simple, durable, practicable and economic construction, the special object of the invention being the detachable and concealable features of the shade-piece, 20 which may be fastened within the fez when not operative as a shield, and when so fastened is not visible from the outside and does not interfere with the comfortable wearing 25 of the fez, and the shade is always handy and ready for immediate use as a shield or shade for the eyes, and which device is facile, efficient and economic and represents an improved result in detachable or disappearing eye shades.

30 The invention consists primarily in a crescent-shaped eye-shade or sun-shield, made of celluloid, card-board, leather, felt, aluminum or other light flexible and durable material, having at each end, and in the 35 middle if desired, an eyelet, snap-fastener or pressure clasp which may be snapped or attached to the corresponding part of such fastener affixed to the interior of the fez. Any suitable form of fastener may also be 40 employed for the purpose of carrying into effect the objects of the invention.

A practical embodiment of the invention is shown in the accompanying drawings forming a part of this specification, and this 45 embodiment will be specifically described, without, however, intending to limit myself to such specific embodiment, as the form of the fasteners may be altered or changed without departing from the spirit or scope 50 of the invention claimed.

In the drawings: Figure 1 is a view in front elevation of a fez equipped with an eye-shield in accordance with my invention, the eye-shield being shown in the operative position. Fig. 2 is a side elevation of a fez 55 equipped with an eye-shield in accordance with my invention, showing the eye-shield in dotted lines in the concealed or inoperative position, and, Fig. 3 is a diagrammatic view of a fez in a flattened condition showing the eye-shield in full lines in operative 60 position, and by dotted lines the manner in which the shield may be swung either to the right or left to concealed or inoperative position. 65

On the drawings, F indicates the fez and E the eye-shade or shield, X, Y, Z, Z' the fasteners, which for the purposes of the invention are preferably of the two-part type, one part or member having a detachable 70 interlocking engagement with the other part or member.

On the interior of the fez, and about half an inch from the edge or rim thereof, are fixed either the male or female members of 75 the fasteners, being the corresponding parts of the fastener members that are on the eye-shade, so distanced and placed as to evenly meet, articulate therewith, and accomplish a fastening or clasp when properly brought 80 together. Three of these fasteners, as Y, X, Z or Y, Z, Z' will accomplish the objects of the invention, the fastener Y or Z respectively in addition to its serving as a fastener, also acting in the capacity of a pivot, 85 on which the eye-shield or shade E is swung from operative to inoperative position, or vice versa. The use of an additional fastener as X or Z' as the case may be provides merely that the eye-shield or shade may be 90 swung either to the right or the left on its pivot Y and secured in the concealed inoperative position.

The fastening members are placed equidistant, on a horizontal line, Y and Z being 95 so positioned that when the eye-shade or shield is clasped in the operative position, it will be immediately in the front part of the fez, just below such emblem or insignia as the fez may have on the front thereof. 100

The third necessary fastening, either X or Z' (where but three fasteners are used) will be, when X is used, to the left of fastener Y and when Z' is used also, it is placed to the right of Z so the fastener members on the eye-shield will articulate with the member on the fez when the eye-shield is in concealed inoperative position, as shown by dotted lines in the drawings. Where but 5 three fastener members are used as X, Y, Z, it will be observed that the member Y acting always as the pivot does not necessarily need to be of a separable form of fastening, since the eye-shield always swings on this fastener as its pivot. Where it is desired, however, to swing the eye-shield either to the right or left, Z becomes the pivot point 10 when the eye-shield is detached at Y and swung to the right to fasten at Z'.

Preferably the clasp employed should consist of a ball and socket member, which could, by pressure, be snapped together to form a clasp, and which permits the clasp to as readily, by pressure, be unclasped, and 20 which by means of the ball and socket member permits of rotation of the two parts of the clasp upon each other. Therefore, by releasing the end of the eye-shade at Z, the shade would thereby be permitted easily to 25 turn upon the clasp Y as a pivot, upward within the fez until the clasp Z articulates and fastens to the clasp X, as shown in Fig. 2. This clasp Y between the eye-shade and the fez acts as a pivotal point upon 30 which the eye-shade swings or turns in moving from operative to inoperative position. This pivotal member Y acts at the same time as a clasp in both the operative and inoperative positions of the eye-shade. This pivotal 35 clasp may or may not be a detachable one.

When it is desired to discontinue using the eye-shade as such, it is released at the fastener Z (and if additional fasteners are used then release all except the pivotal clasp 40 Y) and the eye-shade is then turned upward within the fez upon Y as a pivot until the clasp Z articulates with the clasp X, and by snapping Z to X the eye-shade thereby becomes firmly fixed within the fez, out of 45 the way and out of view. When it is desired to use the eye-shade in the operative position just reverse the operation. This swinging of the eye shield from operative to inoperative position may be accomplished 50 without entirely removing the covering from the head, since the eye shield swings on a pivot perpendicular to the side walls of the head covering adjacent the eye-shield, and can be manipulated simply by slightly lifting or raising the head covering where the 55 shield is attached.

The eyelets in the fez may be attached by sewing to the felt, so that the stitches will not show through to the outside of the fez,

or by metallic fastener, the prongs of which 65 shall not show through; or the eyelets or clasps may be affixed to a piece of cloth or upon tape, by bradding, sewing or other permanent fastening, and then this cloth or tape to be sewed into the interior of the fez at 70 the proper place.

The eyelets or clasps which are on the eye-shade itself may be bradded thereto, or sewed or fixed by metallic fasteners. A flat two-piece fastener is preferable—a two-part 75 pressure clasp or snap fastener which permits of easy unfastening or unsnapping, and which also permits of rotation of the parts upon each other, while maintaining the fastening.

The eye-shade may be made in any color and shape and may vary from crescent to square, but its most satisfactory lines and contour being crescent or rounded, upon either a straight or slightly curved base. It 85 may be flat or curved as will best form a peak.

Having thus described my invention what I claim as new and desire to secure by Letters Patent is:—

1. The combination with an article of head covering, of an eye-shield pivotally-connected with said head covering interiorly and at the front thereof for movement about an axis perpendicular to the side walls of 95 said head covering adjacent the eye-shield whereby said eye-shield can be moved from operative to inoperative positions without removing the head covering from the head, said eye-shield when in operative position 100 depending from the head covering and when in inoperative position being within the head covering, and means between the eye-shield and the head covering for holding the former in its respective positions.

2. A head covering provided on the inner face around the front part of the rim with three or more fastening members, and an eye-shield provided along its inner edge with a pair of fastening members coacting with 110 the fastening members on the head covering, one of the fastening members between the shield and head covering acting as a pivot on which the shield is swung lengthwise to operative position exteriorly of the head 115 covering and to concealed position interiorly of the head covering, the other fastening member on the shield coacting in the concealed position of the shield with one of the fasteners on the head covering and in the 120 exposed position of the shield with another of said fastening members on the head covering.

3. A head covering provided within the same with three fastening members placed 125 in a line adjacent the rim and equidistant, and an eye shield provided adjacent the inner edge thereof with two fastening mem-

bers coacting with the fastening members on the head covering, said fastening members on the eye-shield being placed one near each end of the shield and placed a distance apart 5 equal to the distance between adjacent fastening members on the head covering, one of the fastenings between the shield and head covering acting as a pivot on which the

shield is swung lengthwise to engage the other fastening member on the shield with 10 one or the other of the remaining unengaged fastening members on the head covering.

In testimony whereof I affix my signature.

SIMON N. GAZAN.
